WILLEM JANSEN J. HZN

By Attorney.

UNITED STATES PATENT OFFICE.

WILLEM JANSEN, J. HZN., OF THE HAGUE, NETHERLANDS.

METHOD FOR MAKING BOOTS, SHOES, AND THE LIKE.

1,303,065.

Specification of Letters Patent.

Patented May 6, 1919.

Application filed November 29, 1916. Serial No. 134,163.

To all whom it may concern:

Be it known that I, WILLEM JANSEN, J. Hzn., a subject of the Queen of The Netherlands, residing at 147 Bilderdijkstraat, The Hague, The Netherlands, have invented certain new and useful Improvements in Methods for Making Boots, Shoes, and the like, of which the following is a specification.

- 10 Boots as usually worn do not come up to all requirements which they should answer as regards their exact adjustment and fit. As far as ready-made boots are concerned this is a matter of course, as such boots are 15 made to certain standards and irrespective of the particularities of the feet of the person who is to wear them. But even boots made to measure are always imperfect. Such boots, as is well-known, are almost exclusively made with the aid of boot-trees, which in turn are made to certain measures taken by the shoe-maker. Apart from the fact that to one set of measures quite a number of widely differing boot-trees may be 20 made, it is obvious that with the aid of one boot-tree shoes may be got that differ in many respects. This must be attributed to the fact that the stresses in the upper-leather as same is fastened to the inner-sole 25 cannot practically be measured, so that the leather may be stretched with various tensions. But also if these difficulties could be overcome, it would still be impossible to make a perfectly fitting boot with the aid 30 of a boot-tree, even if the latter were an exact cast of the foot, as in that case no allowance could be made for the changes in the form of the foot as same performs its function.
- 35 My present invention has for its object to obviate these drawbacks; it substantially consists in that the boots are wholly or in part shaped and made on the feet of the person who is to wear them, in such a manner, 40 that the feet during this operation are caused to assume different positions. In this way the live foot is substituted for the dead boot-tree, so that the shoe-maker in stretching the leather can make allowance 45 for the above mentioned changes in the form of the foot. My method may therefore be termed the dynamic method, as contra-distinguished from the static method as hitherto used.

In this connection it may be well for me 55 to make the following remarks:

1. If a boot shall answer all requirements, *i. e.* support or assist the foot in performing its function, it should under all circumstances make a perfect fit around the heel 60 and the instep. Now the heel gage and the instep gage (*i. e.* the circumference of the foot at *a* and *b* respectively in Figure 1 of the accompanying drawing) are minima in the extended position of the foot as per Fig. 65 1; besides the hollow of the foot is deepest in this position. Therefore it is essential that the upper-leather be stretched around the heel and the instep, and fastened to the rear part of the sole, in the said extended 70 position of the foot, when the boot will always snugly fit around heel and the instep, and the tread will assume its correct shape.

2. The leg of the boot should never pinch the ankle or the Achilles' heel, so that same 75 should be stretched around the foot as the latter assumes its flexing position (Fig. 2) when the projection of the Achilles' heel is maximum.

3. In said flexing position also the ball of 80 the foot has its maximum width, *i. e.* the circumference of the foot at *c* (Fig. 2) is maximum; now, as the upper-leather should never exert any pressure on the ball, it should be fastened to the ball part of the 85 sole as the foot assumes its said flexing position.

In view of the foregoing it is proposed to make the boots and shoes according to the method hereinafter set forth in detail, and 90 for the purpose of facilitating the understanding of certain phases of this method, reference may be had to the accompanying drawing, in which:—

Fig. 1 is a more or less diagrammatic 95 view illustrating the human foot in its normal or relaxed position.

Fig. 2 is a view similar to Fig. 1 showing the foot in a flexed position.

Fig. 3 is a plan view of the insole made 100 in accordance with the present method and having thereon a hollow toe form.

Fig. 4 is a section on the line AA of Fig. 3.

Fig. 5 is a view of a complete boot illustrating the normal angle of spring of the sole thereof.

Similar reference characters designate

corresponding parts throughout the several figures of the drawings.

In carrying the present method into effect, it is proposed to first make a print of the client's feet, both in loaded and unloaded condition, in any manner well known in the art, and then from these prints make the inner soles. Then after this has been done it is proposed to attach to the said inner soles in any suitable manner a hollow nose piece preferably of metal and having the desired shape of the boot nose as illustrated in Figs. 3 and 4, *d* being the sole and *e* the hollow metal toe piece. This metal toe piece 10 more or less subserves the function of a retainer for correctly positioning the inner sole on the client's foot during the subsequent fitting operation in connection with the uppers, and as well known may vary according to the shape or fashion of the boots, since it has only limited part in the correct fit of the boots.

In the meantime the shoe-maker determines the desired height of the heel as well 25 as the desired spring of the boots, the spring being the angle between the horizontal plane and that part of the sole which in the unloaded condition of the boot runs up from the ball to the nose (Fig. 5); normally the 30 spring is about 13°.

Thereupon the upper-leather, which does not contain the heel-seam yet, is loosely put around the foot and provisionally held in position, *e. g.* by means of a spring clip. 35 After this has been done, the heel seam may be made to the shape of the foot and the under-leg, and according to what I remarked above sub 1 and 2 this should be done so that the part of the seam along the 40 heel be made in the extended, (*cf.* Fig. 1), and the part along the Achilles' heel in the flexed position (*cf.* Fig. 2) of the foot.

After the heel seam has been made, the stiffener is inserted, when the upper-leather 45 may be fastened to the inner-sole. This operation should also be carried out on the foot of the client. For this purpose the foot should be regulated, *i. e.* brought into the most favorable position from an orthopedic point of view, in order that the boot 50 may exactly fit the foot in its regulated position and consequently support it in the performance of its function; besides, the shoe-maker should during said operation 55 have the faculty of imparting a certain movement to the foot. For carrying this object into effect, the foot should be placed in some suitable apparatus adapted to cause it to assume the different desired positions 60 and secure it in each of these positions, and further adapted to bring the leather under the required tensional stress.

After being suitably secured in the said apparatus the foot is first placed in its extended position as per Fig. 1; then the

upper-leather is drawn in the desired direction, preferably by means of an adjustable load, and, according to what I remarked above sub 1, fastened by some suitable method to the inner-sole from the heel seam 70 along both sides until where the ball begins.

The foot is then, according to my remark sub 3, brought into and secured in its flexed position, (Fig. 2) this being dependent upon the previously determined height of 75 the heel and the spring, both of which should be fixed in the apparatus in order that the foot may assume the correct position. The upper-leather is now no longer held under tensional stress, but instead the sole is stretched in a direction from heel to toe, preferably also by means of an adjustable load, after which the upper-leather is drawn over the hollow piece *e* and further fastened to the sole.

The shoes are now provisionally provided with heels of the required height, after 80 which the client may walk for some minutes in order that the tread and the leg may make a perfect fit around the foot.

The heel and the outer sole may also be fastened to the boot on the foot of the client; as it is essential however that the client shall lose as little time as possible, these operations are preferably carried out 90 in another way. That is to say, the boots are pulled off and placed into a suitable apparatus, adjusted so that the boots assume the spring as previously determined. A molten mass of low fusing point, *e. g.* a suitable metal alloy such as of the Woods metal 95 *i. e.* alloy of bismuth 4 parts, lead 2 parts, tin 1 part, cadmium 1 part, or a mixture of glue and sawdust to which a small quantity, about 2%, of a mixture of acetic acid and a formaldehyde has been added, is now cast 100 into the boots; after solidification this mass prevents undue deformation of the boot tread while the outer sole is being fastened. The boots may now be finished, and the 105 solidified mass removed.

Having now particularly described and ascertained the nature of my said invention and in what manner the same is to be performed, I declare that what I claim is:

1. A method of making boots and shoes on the natural foot as the last which consists in first measuring and fitting the inner sole and placing the upper leather loosely around the foot, then making the heel seam, then, with the foot in its extended position and the shoe parts still *in situ* on the foot, fastening the upper leather to the inner sole from the heel to the ball portion, then, with the foot in its flexed position, fastening the upper leather to the inner sole as far as the front portion is concerned, and finally uniting the outer sole.

2. A method of making boots and shoes on the natural foot as the last which con-

sists in first measuring and fitting the inner sole and placing the upper leather loosely around the foot, then making the heel seam, then, with the foot in its extended position 5 and the upper leather stretched around the heel and the instep, fastening the upper leather to the inner sole from the heel to the ball portion, then, with the foot in its flexed position and the inner sole stretched in the 10 direction from heel to toe, fastening the upper leather to the inner sole, as far as the front portion is concerned, and finally uniting the outer sole.

3. A method of making boots and shoes 15 on the natural foot as the last which consists in first measuring and fitting the inner sole, then placing the upper leather loosely around the foot, then making the heel seam while the foot is in its extended position as 20 far as the heel is concerned and in the flexed position of the foot as far as the further portion thereof is concerned, then, with the foot in its extended position and the shoe parts still *in situ* on the foot, fastening the 25 upper leather to the inner sole from the heel to the ball portion, then, with the foot in its flexed position, fastening the upper leather to the inner sole as far as the front portion is concerned, and finally uniting the outer 30 sole.

4. A method of making boots and shoes on the natural foot as the last which consists in first measuring and fitting the inner sole, then providing the inner sole with a stiff

hollow toe piece, then making the heel seam, 35 then, with the foot in its extended position and the shoe parts still *in situ* on the foot, fastening the upper leather to the inner sole, from the heel to the ball portion, then, with the foot in its flexed position, fastening the 40 upper leather to the inner sole as far as the front portion is concerned, and finally uniting the outer sole.

5. A method of making boots and shoes on the natural foot as the last which consists 45 in first measuring and fitting the inner sole and placing the upper leather loosely around the foot, then making the heel seam, then, with the foot in its extended position and the shoe parts still *in situ* on the foot, fastening the upper leather to the inner sole from the heel to the ball portion, then, with the foot in its flexed position, fastening the 50 upper leather to the inner sole as far as the front portion is concerned, then removing 55 the portion of the shoe thus formed from the foot and placing therein a suitable material for preventing undue deformation during subsequent operations, then uniting the outer sole, and finally removing the said 60 material.

In testimony whereof I have affixed my signature in presence of two witnesses.
